BATHTUB

James A. Tiller, 3801 Kingswood Drive,
Decatur, Ga. 30032

Filed May 18, 1970, Ser. No. 23,053

(Filed under Rule 47(b) and 35 U.S.C. 118)

Term of patent 14 years.

Int. Cl. D23—02

U.S. Cl. D23—55

FIG. 1 is a perspective view of the bathtub embodying the new design.

FIG. 2 is a top plan view thereof.

FIG. 3 is a view thereof looking from the rear in FIG. 1.

FIG. 4 is a cross-sectional view taken on line 4—4 in FIG. 2.

FIG. 5 is a cross-sectional view taken on line 5—5 in FIG. 2.

I claim:

The ornamental design for a bathtub, substantially as shown and described.
